UNITED STATES PATENT OFFICE.

EUGENE F. BEEBE, OF MINNEAPOLIS, MINNESOTA.

RESILIENT MOUNTING FOR WASHING-MACHINE PLUNGERS.

Application filed September 14, 1925. Serial No. 56,241.

This invention relates to an improved resilient mounting for a plunger or similar member, and more particularly relates to such a device adapted for use on washing machines of the type disclosed in my United States Patent No. 1,135,565, to yieldably support the usual vacuum cups or clothes pounders operatively mounted within the machine.

10 An object of the invention is to provide a resilient mounting for plungers constructed in such a manner that the relative movement of the plunger within its supporting means may be considerably increased without increasing the length of the supporting means and without danger of weakening the spring elements mounted therein.

A further object of the invention is to provide a resilient mounting for plungers comprising a plurality of telescoping members having spring elements interposed therebetween tending normally to retain the members in closed normal position.

A further and more specific object is to provide such a mounting having a plurality of different sized spring elements mounted therein and one of said elements being of a relatively larger diameter and arranged to encircle the other elements.

20 A further object is to provide such a structure of simple and inexpensive construction, comprising few parts, and all of such parts being readily interchangeable.

The particular object of the invention, therefore, is to provide an improved resilient mounting for plungers whereby the resilient longitudinal movement of the plungers within their mountings may be relatively increased without adding to the length of the supporting means, and also without danger of impairing the operation of the spring elements mounted therein, thereby providing such a device particularly well adapted for use in washing machines 40 of the above mentioned type to resiliently support the plungers therein.

Other objects of the invention will appear from the following description and the accompanying drawings and will be pointed out in the annexed claims.

In the drawings there has been disclosed a structure designed to carry out the various objects of the invention but it is to be understood that the invention is not confined to the exact features shown as various

changes may be made within the scope of the claims which follow.

In the accompanying drawings forming part of this specification,

Figure 1 is a vertical sectional view of a 60 washing machine showing my invention applied to the plungers thereof;

Figure 2 is an enlarged detail sectional view showing the general construction of one of the resilient mountings;

Figure 3 is a detail view, partially in section, showing the plunger partially compressed;

Figure 4 is a plan view of Figure 2, partially in section, showing the spring retaining nut mounted in the device;

Figure 5 is a perspective view of the nut removed from the device; and

Figure 6 is a detail sectional view of the upper portion of the spring supporting 75 barrel or cylinder showing the bayonet slots provided therein for demountably locking the spring-retaining ring thereto.

In the selected embodiment of the invention here shown for purposes of disclosure, 80 there is illustrated a washing machine of the type above mentioned, comprising a tub 11 mounted upon a suitable frame 12 and having a cover 13 arranged to provide a closure for the tub. The usual mechanism 14 for rotating the tub 11 is shown mounted upon the frame 12 beneath the tub.

The type of machine here shown comprises a pair of vacuum cups 15 secured to the lower ends of a pair of plungers 16 90 which are yieldably supported upon a pair of parallel arms as shown in Figure 1. The upper link 18 is pivotally mounted upon a standard 19 by means of a pin 21 while the lower link 18 is terminally mounted upon a rock shaft 22 having its opposite end operatively connected to a suitable driving mechanism, not shown. Elongated openings or slots 23 are provided in the cover 13 to permit the resilient plunger mountings 100 and the lower arm 18 to operate through the cover as shown.

An important feature of this invention resides in the novel construction of the plunger mountings and the means provided therein for relatively increasing the resilient movement of the plungers 16 with relation to their supporting means, which resilient movement is usually provided to prevent damaging the machine when one of the 110

vacuum cups 15 engages a quantity of clothes in the bottom of the tub, which is of sufficient depth or size to prevent the cup from being moved to the bottom of its normal stroke, as indicated by the dotted lines in Figure 1. Washing machines of this type are therefore usually provided with spring-supported plungers to thus permit the downward movement of the cups to be interrupted before their supporting means have completed their downward movement. Heretofore, difficulty has also been experienced in constructing a resilient mounting for the plungers which would be comparatively small in size and at the same time permit the plungers to relatively move therein a distance sufficient to allow for the clothes packing in the bottom of the tub when engaged by the cup, without danger of damaging the operating mechanism of the machine.

The novel supporting means featured in this invention is particularly adapted for use to overcome the above difficulties, and comprises a tubular or cylindrical member 24 having its lower end bored to receive the plunger 16 as shown in Figures 2 and 3. A sleeve 25 is reciprocally mounted within the cylinder 24 and has an annular outwardly extending flange 26 provided on the lower end thereof which functions to provide a seat for a compression spring 27, and also to provide a guide for the lower end of the sleeve. The upper end of the sleeve 25 is bored as at 25^a to receive the upper end-portion 28 of the plunger 16. A lock ring or nut 29, having opposed lugs 31 formed thereon, is demountably mounted in the upper open end of the cylinder 24 to provide a seat for the upper end of the spring 27 and also to retain it in position therein. The lugs 31 are adapted to be seated in bayonet slots 32 provided in the inner wall of the cylinder 24 adjacent the upper end-portion thereof, as shown in Figure 6.

The bore 33 of the sleeve 25 is of a relatively larger diameter than the diameter of the plunger 16 so as to receive a relatively small compression spring 34 coiled about the upper end-portion 28 of the plunger 16 and having its upper end seated against a shoulder 35 and its lower end against a supporting pin 36, fixedly mounted in the plunger 16 as shown in Figure 2. A cushion spring 37 is also coiled about the plunger 16 and is interposed between the supporting pin 36 and the lower face 38 of the cylinder 24. Suitable apertured lugs 39 are formed on the cylinder 24 to provide means for connecting the cylinder to the forked ends 41 of the parallel arms 18.

In the operation of this novel plunger mounting, the parts will be assembled as shown in Figure 2 wherein the parts are shown in normal position and all of the

springs are preferably under tension. This will readily be seen as a result of the relatively larger spring 27 tending to force the sleeve 25 downwardly against the tension of the spring 34, which obviously acts against the tension of the cushion spring 37 seated upon the face 38 of the cylinder 24. When the plunger is downwardly moved as shown on the left hand side of Figure 1, and the vacuum cup engages a quantity of clothes and is prevented from further downward movement, the cylinder 24 will continue its downward movement as a result of its pivotal connection with the arms 18. Such continued downward movement of the cylinder 24 will cause the upper end-portion 28 of the plunger 16 to be projected out of the upper end of the sleeve 25, which sleeve likewise will be projected from the end of the cylinder 24, as particularly shown in Figures 1 and 3. Such relative movement or telescoping of the upper end-portion 28 of the plunger 16 and the sleeve 25 within the cylinder 24, will cause the springs 27 and 34 to compress as shown in Figure 3, thereby permitting the cylinder to complete its stroke without danger of damaging the operating mechanism of the machine. As soon as the cylinder 24 starts its upward movement the sleeve 25 and the end-portion 28 of the plunger 16 will recede to their normal positions, shown on the right side of Figure 1 and in Figure 2, before the cup 15 will be lifted from the clothes.

Thus it will readily be noted that by mounting the compression spring 34 within the relatively larger compression spring 27, that the travel or relative movement of the plunger 16 with relation to the cylinder 24 may be considerably increased without danger of overloading the springs. Upon the upward stroke or movement of the plunger the cushion spring 37 may be subjected to a slight load as a result of the suction or vacuum created in the cups in lifting them out of the water. It will also be noted that the plunger will be supported entirely upon springs so that it will be free to move within the cylinder 24 when engaging the clothes as shown in Figure 1. The locknut or ring 29 provides means whereby the mounting may readily be disassembled when necessary for repairs or for other reasons.

In the drawings I have shown the invention as applied to a washing machine, but it is to be understood that its use may be extended for other purposes without departing from the invention.

Having thus described my invention what I claim as new and desire to secure by Letters Patent is:

1. A device of the class described including a cylinder having a plurality of telescoping members mounted therein, one of the members having a vacuum cup, and

means for yieldably retaining said members in normal retracted position.

2. A device of the class described including a cylinder, a plurality of telescoping members mounted therein one of said members carrying a cup, and spring elements interposed between said members to normally retain them in retracted position.

3. A resilient mounting for plungers, comprising in combination a cylinder, a sleeve reciprocally mounted therein, a plunger arranged in the sleeve said plunger having a washer element connected therewith, bearings in said cylinder and said sleeve for supporting the plunger, and spring elements interposed between the cylinder and the sleeve and also between the sleeve and the plunger to normally retain said sleeve and said plunger in normal retracted position within the cylinder.

4. The combination with a cylinder, a sleeve slidable therein, of a plunger slidable in the sleeve and having a washer element, a spring adapted to be compressed by movement of said plunger in one direction, and a second spring adapted to be compressed

simultaneously with said first named spring to permit additional movement of said plunger.

5. In a washing machine, a cylinder 30 mounted for vertical oscillation, a sleeve mounted to slide vertically in said cylinder, a compression spring normally resisting upward movement of said sleeve, a vacuum cup having a plunger slidable within said sleeve, and compression springs on said plunger between the cylinder and sleeve adapted to resist relative longitudinal movement of said sleeve and plunger.

6. A device of the class described, including a cylinder, a sleeve slidable in said cylinder, a spring arranged to urge the sleeve toward one end of the cylinder, a plunger slidable through and guided in said cylinder and sleeve, a pair of compression 45 springs, each having one end abuttingly engaging the plunger, and having their opposite ends respectively engaging the sleeve and cylinder.

In witness whereof, I have hereunto set 50 my hand this 11th day of September 1925.

EUGENE F. BEEBE.
